ANIMAL FEED FLOW MONITOR

Gerald L. Kitson, 9709 Belding Road,
Rockford, Mich. 49341

Filed Oct. 9, 1973, Ser. No. 404,701

Term of patent 14 years

Int. Cl. D30—03

U.S. Cl. D30—13

FIG. 4

FIG. 2

FIG. 1

FIG. 3

FIG. 5

FIG. 6

FIG. 1 is a side elevational view of an animal feed flow monitor showing my new design, an intermediate portion being broken away and omitted for ease of illustration;

FIG. 2 is a rear elevational view thereof;

FIG. 3 is a front elevational view thereof;

FIG. 4 is a top plan view;

FIG. 5 is a bottom plan view; and

FIG. 6 is a perspective view.

I claim:

The ornamental design for an animal feed flow monitor, as shown and described.
